(57) **CLAIM**

The ornamental design for an expandable table as shown and described.

DESCRIPTION

FIG. 1 is a rear perspective view of the expandable table in a closed position of use, showing my new design;

FIG. 2 is a front elevational view of the expandable table of FIG. 1;

FIG. 3 is a right side elevational view of the expandable table of FIG. 1;

FIG. 4 is a left side elevational view of the expandable table of FIG. 1;

FIG. 5 is a top plan view of the expandable table of FIG. 1;

FIG. 6 is a rear elevational view of the expandable table of FIG. 1;

FIG. 7 is a bottom plan view of the expandable table of FIG. 1;

FIG. 8 is a right side elevational view of the expandable table of FIG. 1 in an expanded position of use; and,

FIG. 9 is a left side elevational view of the expandable table of FIG. 1 in an expanded position of use.

The broken lines show features that form no part of the

claimed design.
